DEVICE FOR CUTTING, PUNCHING, AND DRILLING SECTION IRON

Joseph Goreth, Leipzig, Germany

Application April 7, 1933, Serial No. 664,957
In Germany July 2, 1932

8 Claims. (CL. 29—33)

This invention relates to a mechanical-automatic method of and device for cutting, punching, and drilling the material for use in the iron and constructional steel working-up industry, 5 without the employment of a center-point or other marking elements.

My improved method consists in placing the material to be cut, punched, and drilled, on a carriage adapted to travel on tracks mounted on frameworks, causing the said carriage with the material thereon to advance by the operation of a gear-feed, controlling the feed motion by a steel tape-measure, causing said steel tape-measure to travel in unison with said carriage designed to bring the material in question in succession to the machines for cutting, punching, and drilling, and spacing the feed motion without the aid of special stopping devices or any other auxiliary means, and without the use of a center-point or other marking-off elements. My improved method of cutting, punching, and drilling the material further consists in clamping a plurality of section iron pieces adjacent to one another, guiding said clamped section iron pieces 20 between supporting rollers, causing said clamped section iron pieces to advance along the devices for cutting, punching, and drilling, and underneath thereof, and providing means for causing said clamping and guiding devices to occupy a position transversely of the tracks, for the purpose of positioning the said section iron pieces under the respective tools for cutting, punching, and drilling.

The invention further comprises a device suitable for carrying out automatically and mechanically the method of cutting, punching, and drilling sectional iron pieces, the said device having the advantage of obtaining cutting, punching, and drilling of the material without the employment of a center-point or other marking elements. The main object of the invention is to provide frameworks having tracks mounted thereon and carriages adapted to travel on said tracks, the said carriages having the function to feed the material to be treated step by step. Another object of the invention is to place the pieces of work in an accurate longitudinal direction and to provide for this purpose an endless tape-measure which is secured to the respective framework and in firm connection with the said feed carriages.

A further object of the invention is to equip the carriages with means for clamping the pieces of work thereon and to have said clamping means adapted for adjustment in, respectively,

vertical and transverse positions to the feed motion. A still further object of the invention is to provide means for guiding and tensioning the said tape-measure, which carries an indicating scale, and to provide means for preventing said tape-measure from sliding. A still further object of my invention is to provide guides in close proximity to the punch and drill places, and to have the structure of these guides adapted to the different shapes of the section iron pieces, 10 the said guides having the function of holding the pieces of work in proper position in front of the respective working tool. A still further object of my invention is to provide each one of the carriages designed for use with the device for punching, with a table adapted for adjustment in the vertical plane, said tables being equipped with laterally adjustable clamping devices, and spindles being provided for operation of both the tables and the clamping devices, respectively. A still further object of my invention is to provide at both sides of the punch place, guide means adapted for movement in transverse direction with respect to the feed motion and intended for accurate adjustment of 20 indicating scales, and to provide means for accomplishing adjustment of said indicating scales. A still further object of my invention is to provide the carriages adapted for use with the device for drilling, with elements having in part to 30 serve as stops and in part as clamping-up members, respectively, a threaded spindle being provided to connect with one another the said stop members and the said clamping members for operation in such a manner that the adjustment 35 of the said stop members is followed by the clamping-up action of the other members. A still further object of the invention is to provide, in proximity to the drill place, guide means for supporting a plurality of section iron pieces, the 40 said guide means being adapted for movement into transverse position with relation to the tracks and disposed uniformly in spacings corresponding to the spacings existing between the 45 drill spindles. And a still further object of the invention is to provide rollers for supporting the extremities of the angle iron pieces.

In the accompanying drawings which form a part hereof and in which like characters designate similar parts throughout the several views, I have exemplified a preferred construction of the devices designed to carry out the method of cutting, punching, and drilling section iron in accordance with my invention. It is to be understood, however, that I do not wish to be 50 55

limited in any way to the devices shown, since I am aware that various changes and modifications may be made within the purview of my invention and without departing from the spirit thereof. The objects of my invention will be hereinafter referred to and the novel elements and combination of elements whereby they may be obtained, will be more particularly set forth in the claims appended thereto.

10 In the drawings:

Fig. 1 is a side elevation of my improved cutting device according to the invention.

15 Fig. 2 is a top plan view, detached, of the feed carriage, and a top plan view, detached, of the adjusting gauge together with the adjustable stop,

20 Fig. 3 is a top plan view, detached, of the means for raising and lowering the gauge together with the adjustable stop,

Figs. 4 to 7, inclusive, show details,

25 Fig. 8 is a side elevation of the punching device,

Fig. 9 is a plan view thereof,

25 Fig. 10 is an end elevation, thereof, detached,

Fig. 11 is an end elevation, detached, showing the piece of work in position for feed,

Fig. 12 is a side elevation of the drilling device,

30 Fig. 13 is a top plan view thereof, and

Figs. 14 to 17, inclusive, show details of my improved device for drilling section iron.

In the practical embodiment of my invention, and with particular reference to Figs. 1 to 7, I provide two frameworks, as at 1 and 2, the said frameworks which differ in structure from each other, being disposed, respectively, at the left hand side and at the right hand side of the cutting device or shears 123. The

40 framework 1 which is situated in front of the shears 123, is positioned at a distance of about 800 millimeters from the center of said shears, thus leaving a space for the attendant. On the said framework 1, there are mounted tracks 3 and 4 composed of U-shaped rails and upon which a carriage or truck 5, serving for the forward transport of the material to be cut, is adapted to travel. As the profiled cutting blades of the shears 123 are occupying different heights and positions, the said truck is pro-

45 vided with means for feeding the material to be cut accordingly. To this end, said truck carries a table 6 adapted to be raised and lowered by means of a worm-gear which comprises the worm wheels 7 and 8 in connection with pressure spindles 9 and 10, respectively, and intermeshing with the worm 11, which has attached thereto a crank-handle 12 for operation. The said table has pins secured to both its sides, these pins being designed for engagement with slots provided in laterally mounted plates of sheet iron 13 and 14, respectively, and

50 serving as a guide for said table. Upon the latter is located a clamping device for firmly holding the material to be cut, this device having jaws like those of a vice, as at 15 and 16, and each one of said jaws being adapted for movement in either direction by the operation of a crank-handle 19. The one of these jaws,

55 that is to say that one which is lying opposite the cutting device, has the function to act as a stop for the material to be cut, and the other jaw has to exert the clamping-up action. Owing to this arrangement, clamping of the material to be cut is rendered possible in accord-

5 ance with the positions of the cutting blades of the shears, irrespectively of the positions occupied by said blades. In order to have accurate positioning of said stop-jaw and of said table readily obtained, there are applied to said truck a number of marks which indicate the different positions occupied by said blades.

10 The framework which is situated behind said device for cutting, comprises standards, the forwardly disposed ones of which are each composed of four angularly shaped pieces 124 arranged in the form of a cross and between which are guided rack bars 20 adapted for up-and-down movement. Intermediate the members 20 and 21 are disposed flat iron pieces, which are made 15 to penetrate at both sides between said angularly shaped pieces and guided therein. A U-shaped rail 22 which occupies a transverse position upon said rack bars 20, serves as adjusting gauge for the various lengths of the material and is provided with an indicating scale 22', as clearly shown in Figures 1 and 2. The said scale is graduated in millimeters from 0 up to 12000 and more, as the case may be, the said 20 graduations being made so that the first three 25 or five meters are divided into millimeters, whereas the remainder of the scale carries marks of division from 5 to 5 millimeters. On the U-shaped rail 22 is slidably mounted a stop 23 (see Figure 2) fitted with two screws 24 for 30 clamping purposes. To prevent deflection of the profile rods during the cutting action, the said rack bar members 20 and the U-shaped members 21 are provided with angle tables having sliding rollers 25 upon which each rod is 35 to be supported. In the case of rods of short length having to be cut, the said angle tables must be removed from the said members 20 and 21, respectively.

40 Raising and lowering of the said adjusting gauge together with said stop are obtained by means of a shaft 26 and toothed wheels 28, the said shaft being journaled in single bearings 27 and adapted for operation by a crank 29, as shown in Figure 3. In the body of the device 45 for cutting, there has been provided a passage, and through this passage, said shaft extends so that the attendant who is to occupy the space left between framework and cutting device, is able to operate the shaft 26 by means of 50 said crank-handle 29 (see Figure 3). In order to have said arrangement secured against any displacement, the crank-handle 29 is provided with two flat iron pieces 30 disposed adjacent to and connected with each other by means 55 of intermediate members constituting a whole of circular shape. This ring shaped member is provided with holes having marks applied thereto and which are adapted for the selective reception of a split-pin 31, this split-pin having 60 thus to serve as a support for said crank-handle 29 in its locked position.

65 As clearly shown in Figure 7, there are provided strippers 32 which have for their office to throw down the material cut off the supporting 65 rollers 25. The said strippers carry at top and base cranked flat iron pieces and are intended to be clamped to the upper and lower connecting pieces of angular shape at suitable places thereof, a set-screw 33 being provided for securing said strippers against displacement. If required, each stripper may be mounted so as to be adapted for adjustment in height.

70 As exemplified, the invention has for its object a cutting device of the section iron and 75

angle iron shears type, which may be easily combined with a device for punching, as shown in Figure 5. As soon as one rod has been cut off and is in supporting position upon the said 5 sliding rollers, the latter are lowered until said rod is in supporting position on the respective stripper, from which the rod is then gliding off, whereupon the rollers are returned.

The device for punching is mounted upon a 10 framework 125 composed of angularly shaped iron pieces and having preferably an extent of 15 meters in working length, and a suitable height measuring about 1050 millimeters from top to lower center of punch. Upon said framework, 15 there are disposed tracks in the nature of U-shaped rails 36, on which a carriage 37 carrying the material to be punched, is adapted to travel at the left hand side of the punching device, and a carriage 38 having to transport 20 the material punched, is adapted to travel at the right hand side of the said punching device. A rope drive 39 disposed on pulleys 40, is provided for imparting movement to said carriage in either direction, operation of said pulleys 25 being effected either by a motor of 1 HP or by a motor with gearing of any kind. Forward feeding of said carriage which feeding may have an extent of about 250 millimeters, may be either obtained by said motor drive or by hand 30 operated means. To this end, a toothed wheel 42 is keyed to the driving shaft, said wheel being operated by the driving chain 42 and the toothed wheel 43 to which is attached a crank-handle 44. The steel wire drive is at the free 35 extremity of the framework fitted with an automatic tensioning device 45 with weight 46 to prevent slackening of rope.

Rollers 47, 48 are secured to the tracks constituted by the U-shaped rails 36, the said rollers being adapted for guiding and supporting a steel 40 tape-measure 49 having preferably 40 millimeters in breadth and carrying indicating gradations in millimeters over 15 meters of its length. The said tape-measure is of the endless type and provided with perforations with 45 which the two end-rollers 50 having tooth-like projections 50' for that purpose, are made to engage to prevent said tape-measure from sliding. At the extremity of said framework, there 50 is located an element 51 of suitable type, this element serving as a tensioning means for said tape-measure which is protected by a box 52. Suitable devices are accommodated at the left 55 hand side and at the right hand side of the matrice support 70, these devices having for their office to operatively adjust the marking gauges for the material to be punched. The said devices comprise, on the one hand, indicating scales 127, and on the other hand, jaws 53 which are guided positively, a rack-bar 54 positioned below said jaws, being in engagement 60 with toothed wheels 55 suitably mounted between said jaws. The operation of said wheels by means of the crank-handle 56 attached thereto, causes said jaws to be brought in proper 65 relation with respect to the work to be done. Sliding rollers 57 are suitably accommodated and adapted to convey the material to be treated with great facility so as to avoid undue friction.

70 In order to secure most exact measuring at the punch place, there is mounted intermediate the said jaw members 53 by a bridge piece 128 which is also supported in sliding rollers 129.

The carriages or trucks 37 and 38 each are 75 equipped with a table adapted to be raised and

lowered by means of worm-wheels 58 and 59, respectively, intermeshing with a worm 60, to be operated by a crank-handle 61. Owing to this arrangement, punching of profile material up to 5 300 millimeters extent in height, is rendered possible. Upon each one of the said tables are mounted jaws 62 which are in the shape of vice-jaws and adapted for clamping the material to be treated between them. Each one of the 10 said jaws is adapted for movement in either direction, operation of said jaws being performed by means of a spindle 63 and a crank-handle 64 attached thereto. An indicating scale 130 is provided to permit of an accurate adjustment of the piece of work so as to position it in the 15 center line of the punch. A flat-iron hinge 65 carrying a bolt 66 is provided, said bolt having to serve as a catch for the piece of work to be punched. A square iron member 67 is fixedly secured upon the carriage 38, the said square iron being designed to act as a stop for the first 20 perforation to be punched. The operation is as follows:

After adjusting the tables of both carriages in accordance with the required profile height, 25 at which punching is to be proceeded with, the piece of work, in the present instance an angle iron 69, is placed so that its ends are supported, on the one hand, by the matrice standard 70, and on the other hand, by the feed carriage 37, 30 to which latter the angle iron is clamped in such a position as to correspond exactly to the axis of the marking gauge. After adjustment of the 35 said marking gauge, the piece of work is, for the purpose of punching the first perforation, caused to move toward the stop member 67, 68 until contacting with same, and after having said carriage adjusted accordingly, the device is ready 40 for operation. As soon as the first perforation has been punched, the catch-bolt 66 is being 45 inserted into said perforation, and punching of the following perforations may be immediately proceeded with owing to the carriage 38 being in connection with the piece of work by means of the said catch-bolt. The steel tape-measure 49 is secured to the carriage 38 laterally thereof. Then, the said carriage together with the piece 50 of work and the steel tape-measure is moved forwardly in accordance with the predetermined spacings, and such operation is continued until 55 all of the perforations are punched.

The electromotor which has to operate forward motion of the said carriage, is of the quick break double-throw knife switch type and additionally fitted with a self-acting magnetic brake. 55 The accurate measuring device which has to perform the said adjustment as hereinbefore described, allows of a correct reading-off. The center of the punch is marked by a fixedly secured indicating hand, below which the tape-measure is caused to advance on a sliding plate. The beginning of the punching action corresponds to the graduation "0" of the tape-measure, therefore corresponds to center of punch, and likewise, the center of the catch-bolt 66 is indicated by the graduation "0", this position of the 60 said catch-bolt thus corresponding also to center of punch. The attendant is in possession of a "list of punching" adapted to each case, from which list the spacings required are to be read off and according to which list the truck carrying the piece of work, has spacing by spacing to be advanced and the perforations punched. 65 As hereinbefore described, only the following 70 manipulations are necessary: Placing the piece 75

of work upon the carriage, adjusting the carriages at proper height, adjusting the marking gauge, mounting, at the beginning of the punching action, the stop member in view of the first 5 perforation to be punched and removing thereupon the said stop member, correct reading off during the punching action, and accurate spacing adjustment. When so arranged, adjusted and operated, all of the perforations will be 10 punched in most exact manner.

The device for drilling comprises two stationary iron scaffolds 81 and 82, respectively, of identical structure, the former being disposed at the left hand side of the boring machine, and 15 the latter at the right hand side thereof. Upon both iron scaffolds, which are in connection with each other, are mounted tracks 85 and 86 constituted by U-shaped rails and on which the carriages 83 and 84 are adapted to travel in a 20 positive manner. Of these carriages, the one 83 has for its office to feed the material to the drilling device, and this carriage is provided with an interchangeable sub-table 131, adapted for the 25 reception and for clamping thereto of the material to be drilled; the said clamping operation being obtained by means of four members in the shape of jaws 87, as shown in Figure 14, the said jaw members being intended for operation by the spindle 89 and its crank-handle 90 in 30 either direction at pleasure. The arrangement is made so that with the aid of an indicating scale provided, all of the said jaws which have to serve as stops for the backs of the angle iron pieces to be drilled, are capable of simultaneous 35 adjustment in the longitudinal direction with respect to the axis of the drilling machine spindle. The spaces intermediate said jaws correspond exactly with the guide means provided at the drill place in such a manner that, as 40 exemplified, the four angle-iron pieces will all be positioned on one and the same line. After placing each one of the said angle iron pieces in suitable position between the stop-jaws, the four jaws 88 which are provided for that purpose, 45 are by the operation of a spindle 91 and crank-handle 92, simultaneously moved so as to cause clamping of the said angle iron pieces. In close proximity to the drill place, there is 50 accommodated a sub-table 132 like that carried by the truck 83, as clearly shown in Fig. 15. A plurality of jaws 93 are provided, and all of these jaws are connected with one another by means of a spindle 94 having attached to it a 55 crank-handle 95 for simultaneous operation of said jaws in either direction. Said jaws 93 are spaced from one another in accordance with the 60 spacings existing between the said jaws 87, and they are likewise adjustable with respect to the axis of the drill-spindle, an indicating scale 133 being provided for that purpose. It follows 65 therefrom that, owing to the intermediate spacings between the jaws 87 being identical with those between the jaws 93, the marking gauges of the pieces of work (angle-iron, channel and T-iron) to be drilled will at the drill place be also identical. The material to be drilled, in the present instance angle-iron pieces, is guided 70 in a positive manner in proximity to the drill place, and its feed is assisted by the following arrangement. Rollers 96 having an oblique position are provided and adapted to travel at top and bottom in a pin, the said rollers being designed to take up the angle side pressure during the drilling action. The said rollers are of conical shape, and owing to this construction, con-

tact is forcibly maintained with the inner round corners of the angle-iron pieces so as to avoid a rough drill. Between the jaw members above referred to, there are accommodated supporting rollers for the said angle-iron pieces to be drilled. By means of the arrangement described, there may be drilled four angle-iron pieces of from 25 to 200 m/m on the said sub-table simultaneously, irrespectively of the shape of these pieces which may have equal or unequal sides. 10 The said rollers 96 are mounted on a common flat iron bar 135 in such a manner as to allow of their tipping from one side to the other for the purpose of reversing the position of the pieces of work and of having the other angular side thereof drilled. Each one of the pieces of work is at the drill place guided so as to avoid rough drilling thereof. 15 The carriage as at 84 has to serve as a stop for the first hole to be drilled and is adapted for adjustment in view of the following perforations to be drilled. Upon the said carriage, there is mounted a second one, as at 97, this second carriage being provided with a support 98 in which are accommodated movably disposed jaw members 99 in connection with a common spindle 100 and intended for simultaneous operation by a crank-handle 101 in the same manner as the jaw members 87 and 93, respectively. The said jaws 99 have each a square-iron member 102 which serve as a stop and are fastened to the support 98. Owing to a shifting movement being imparted to said jaws together with their square-iron members, the latter will become positioned so as to contact with the material to be 20 drilled. The carriage 97 is, at the start of the drilling action, so locked to the carriage 84 as to render displacement of the same impossible, even if heavy shocks should occur. The support or table 103 provided is identical with that belonging to the carriage 83. To said support are at the proper moment clamped the pieces of work to be drilled, thereby realizing a connection with the feed carriage 84. In order to avoid displacement of even most minimal extent, the 25 locking means provided are assisted by a catch-member. 30 As exemplified in Figure 17, there is provided a device, as at 104, adapted to be raised and lowered by means of a rack-bar 136 in view of having the perforations drilled in accordance with the linear and root-scales, respectively. Intermediate the said device which is movable within guides 137, made in the structure of flat iron, there are accommodated two jaw members 105 35 also adapted to be raised and lowered, and intended for operation by a spindle 106 having a crank-handle 107. Both jaws are connected with each other by means of a bracket forming a bridge or yoke 108 over the object to be drilled, 40 the said bridge being adapted for horizontal movement in either direction and for raising and lowering, and having attached to it laterally a die-rod 109, the said attachment being obtained by inserting said rod into the body of 45 said bridge and securing it against displacement. There is but one die-rod required for drilling perforations of any diameter in angle-iron, channel, and T-iron. To this end, drill bushes corresponding in cross-section to the various 50 diameters of the perforations, are employed, the arrangement being made so that a number of holes, in the present instance four, are provided in said die-rod, and these holes which have a diameter of 36 millimeters, are adapted for 55 70 75

the reception of the respective bushes. Owing to the fastening of said bushes being made removable, an easy mounting and dismounting of said bush members will result therefrom. A 5 steel tape-measure 112 supported on rollers 110 and 111, respectively, and adapted to travel laterally of the framework, allows of the adjustment of the spacings. The said steel tape-measure which is of the endless type like that 10 employed with the device for punching, is provided with graduations in millimeters and protected by a sheet iron cover 113; it has 40 millimeters in breadth, and its length corresponds to the extent of the framework. To prevent 15 sliding of the tape-measure, the same is provided with perforations 139 with which two end-rollers 114 are made to engage, the said rollers being for that purpose fitted with projections or teeth. The device 115 serves as tensioning 20 element for said tape-measure. In close proximity to the reading-off place, the tape-measure is caused to travel upon a plate. The reading-off place, in the present instance center of drill spindle or graduation "0", is occupied by a hand 25 116 which is of the illuminated type and allows of a quick reading-off. Feed of the carriage together with the piece of work at the left hand side of the punching device, which feed is limited to a but short extent, say to about 500 30 millimeters, is obtained by a single rope tackle block guided over two pulleys adapted to be operated by a crank-handle. When the carriage is without charge, the said rope tackle block may be thrown off and the carriage pushed 35 back by hand. To the truck or carriage at the right hand side of the boring machine is attached an endless rope 117 which is guided over pulleys 118 and 119, respectively, so as to allow of its right and left travel. To prevent 40 slackening of rope, the same is connected to an automatic tensioning device 120 having a counter-weight 121. With boring devices for heaviest charges, there may be provided a chain drive in lieu of the said rope tackle block. The 45 operation is as follows:

The material to be drilled, in the present instance angle-iron pieces, is after completion of the cutting action by the cutting device, placed so that its ends are supported, respectively, on 50 the carriage 83 and on the sub-table or support 103, and clamped. The steel tape-measure is in connection with the carriage 97 in such a manner that, the said carriage being in starting position, the graduation "0" of the tape-measure corresponds to center of drill spindle. 55 Both carriages may by hand operated means be locked so as to prevent displacement thereof, even if hardest shocks should occur. As hereinbefore described, stops 102 are carried by said carriage 97, the said stops being adapted for movement toward one another and intended for adjustment of the first, second, and eventually third perforations, according to the spacings existing. Let it be supposed that the first 60 perforation should be drilled at a distance of 40 millimeters from the extremity of the piece of work. Consequently, the tape-measure is to be adjusted so that the hand points to 40 millimeters. As the said tape-measure and the said 65 wire rope drive are both connected to the carriage 97, forward feeding of the tape-measure in unison with the wire rope results therefrom. When so adjusted, the pieces of work to be drilled are, by the use of the manually operated 70 mechanism at the left hand side of the boring

machine, then brought in close proximity to said machine. It is to be noticed in this respect that all of the pieces of work to be drilled are positioned so as to be uniformly spaced from one another, and so are the root-scales, too. Therefore, the holes provided for in the drill-die or die-rod 100 have also corresponding spacings. Then, the bed is adjusted in accordance with the marking gauge and positioned upon the piece of work by means of the raising-and-lowering device 104. The latter and the bed are in an absolute manner secured against vibration. The bed remains always the same, except however for drilling sheet-iron, and it is only necessary to adapt it to the different 15 marking gauges by means of a few rotations of crank. The pieces of work being brought in contact with said stop and the bed adjusted, drilling of the first hole may be proceeded with. For the drilling of the following perforations, 20 it suffices to adjust the required spacings with the aid of the tape-measure. The first perforation being drilled, the carriage 97 together with the stop 102, is caused to move forward upon the carriage 84 to a sufficient extent and to 25 occupy a new position in which it is locked by manually operated means. As soon as said carriage is occupying this new position, the piece of work to be drilled has reached the device 103 and is clamped therein. The electro- 30 motor is then started and causes forward feeding of the carriage and the tape-measure. The motor is of the reversible rotary switch type and fitted with a self-acting magnetic brake for instantly stopping. A hand operated toothed 35 wheel drive 122 is provided and adapted to accomplish accurate adjustment. The guide members accommodated at the drill place, as exemplified in Figure 15, are not stationary, but adapted for lateral tipping by means of hinges 40 provided, so that any piece of work may be bored at either side and without causing displacement of the support.

The drilling machine described may be jointly 45 employed as punching machine. All of the means provided remain unchanged, with the exception however of the bed which is made sinkable and which is to be substituted by the device for adjusting the marking gauges. The whole arrangement, in lieu of being stationary, 50 may be movably mounted, so that the device for drilling may be shifted to the device for punching, and vice versa, and in this way used for punching or drilling purposes, as the case 55 may be. Besides, the punching device in connection with a cutting device for section iron, may be combined with a device for cutting profile rods of any kind, without the employment of special marking elements (see Figure 5).

What I claim is:

1. A device suitable for cutting section iron, comprising two frameworks of different construction, shears mounted thereon, the said frameworks being disposed, respectively, at the left hand side and at the right hand side of said 65 shears, tracks mounted on the frame work situated in front of said shears, a carriage adapted to travel on said tracks, a table mounted on said carriage, a clamping device for securing the material to be cut to said table, means for raising and lowering said table, and means for imparting motion to said carriage which is designed to feed the material to the cutting device.
2. A device suitable for cutting section iron, comprising two frameworks of different con- 70

- struction, shears mounted thereon, the said frameworks being disposed, respectively, at the left hand side and at the right hand side of said shears, tracks mounted on the framework which is situated in front of said shears, a carriage adapted to travel on said tracks, a table mounted on said carriage, means for raising and lowering said table, said means comprising worm-wheels and a worm intermeshing with said worm-wheels, pressure spindles in connection with said worm-wheels, a crank-handle for operating said worm, plates of sheet iron mounted laterally of said table, slots provided in said plates of sheet iron and means for engagement with said slots, this means serving as a guide for said table, means for securing the material to said table, said means comprising clamping jaws, each one of said jaws being adapted for movement in either direction, a crank handle for operation, one of said jaws having the function to act as a stop for the material to be cut, marks applied to said carriage, said marks allowing of accurate positioning of said stop-jaw and of said table with respect to the different positions occupied by the cutting blades of the shears, and means for imparting motion to said carriage which is designed to feed the material to the cutting device.
3. A device suitable for cutting section iron, comprising two frameworks of different construction, shears mounted thereon, the said frameworks being disposed, respectively, at the left hand side and at the right hand side of said shears, tracks mounted on the framework which is situated in front of said shears, a carriage adapted to travel on said tracks, a table mounted on said carriage, means for raising and lowering said table, said means comprising worm-wheels and a worm intermeshing with said worm-wheels, pressure spindles in connection with said worm-wheels, a crank-handle for operating said worm, plates of sheet iron mounted laterally of said table, slots provided in said plates of sheet iron and means for engagement with said slots, this means serving as a guide for said table, means for securing the material to said table, said means comprising clamping jaws, each one of said jaws being adapted for movement in either direction, a crank-handle for operation, one of said jaws having the function to act as a stop for the material to be cut, marks applied to said carriage, said marks allowing of accurate positioning of said stop-jaw and of said table with respect to the different positions occupied by the cutting blades of the shears, the said framework situated behind said shears comprising standards, of which the forwardly disposed ones are each composed of four angularly shaped iron pieces arranged in the form of a cross, rack-bars guided between said angle pieces and adapted for up-and-down movement, flat iron pieces adapted to penetrate between said angular pieces at both sides thereof, a U-shaped rail occupying a transverse position upon said rack-bars and serving as adjusting gauge for the various lengths of the material, an indicating scale carried by said U-shaped rail, a stop slidably mounted on said U-shaped rail, screws fitted to said stop, angle tables removably mounted on said rack bars, U-shaped members, angle tables removably mounted thereon, sliding rollers in connection with all of the said angle tables and adapted for supporting the material, means for raising and lowering said adjusting gauge together with said stop, said

means comprising a shaft and toothed wheels, a crank-handle for operation, means for securing the said arrangement against displacement, said means comprising flat iron members in connection with said crank-handle and connected to each other by circularly shaped members, perforations provided in said circularly shaped members, marks applied to said perforations, these perforations being adapted for the selective reception of a split pin serving as support for said crank-handle in its locked position, strippers adapted to throw down the material cut off from the said supporting rollers, cranked flat iron pieces carried by said strippers at top and base thereof and intended for being clamped to the upper and lower connecting members of angular shape, a set screw for securing said strippers against displacement, and means for imparting motion to said carriage which is designed to feed the material to the cutting device.

4. A device suitable for drilling section iron, comprising two stationary iron scaffolds of identical structure and disposed at both sides of the drilling device, tracks mounted upon both scaffolds, a carriage adapted to travel on said tracks and having the function to feed the material to the drill and to serve as a stop for the first perforation to be drilled, a sub-table mounted on the first one of said carriages, means for clamping said material to said sub-table, said means comprising clamping jaw members disposed in transverse position to the said tracks, a spindle for simultaneous operation of said jaw members, an indicating scale, and guide means provided at the drill place.

5. A device suitable for carrying out the method of punching section iron, comprising a framework composed of angularly shaped iron members, tracks disposed on said framework, said tracks being in the nature of U-shaped rails, a carriage with the material to be punched being adapted to travel on tracks at the left hand side of the punching device, a second carriage for the transport of the material punched being adapted to travel on tracks at the right hand side of the punching device, a rope drive for imparting motion to said second carriage, rope pulleys having grooves disposed in a helical line intended for the reception of a steel wire-rope for imparting movement to said second carriage in either direction, means for operating said drive, this means comprising a driving shaft and a toothed wheel keyed thereto, a driving chain adapted for operation of said toothed wheel by means of a second toothed wheel having a crank-handle attached thereto, an automatic tensioning device for said steel wire drive, rollers secured to said tracks, an endless steel tape-measure supported on and guided by said rollers, perforations made in said tape-measure and adapted for engagement with end-rollers carrying projections, means for tensioning said tape-measure, a protecting cover for said tape-measure, means disposed at both sides of the matrice support and adapted for adjustment of the marking gauges, this means comprising indicating scales, and positively guided jaw members, and a rack-bar positioned below said jaw members, and toothed wheels in engagement with said rack-bar and mounted between said jaw members, a crank-handle for operating said toothed wheels, said operation causing said jaw members to be brought in operative position, sliding rollers adapted to convey the ma-

- terial to be treated, a bridge piece mounted intermediate said jaw members and having the function to secure most exact measuring at the punch place, sliding rollers for supporting said bridge piece, a table mounted on each one of the said carriages, means for raising and lowering said tables, this means comprising worm-wheels, and a worm intermeshing with said worm-wheels, and a crank-handle for operation, 10 jaw members mounted on each one of said tables, the said jaw members being in the shape of vice-jaws and adapted for clamping the material to be punched between them, one of said jaw members being adapted for movement in either direction, a spindle and a crank-handle for operating said jaw members, and indicating scale for accurate adjustment of the piece of work, a flat iron hinge, a bolt carried by said hinge and serving as a catch for the piece of 15 work, and a square iron member fixedly secured on the said second carriage, the said square iron member being adapted to act as a stop for the first perforation to be punched.
6. A device suitable for drilling section iron, comprising two stationary iron scaffolds of identical structure and disposed at both sides of the drilling device, tracks mounted upon both scaffolds, carriages adapted to travel on said tracks and having the function to feed the material to the drill and to serve as a stop for the first perforation to be drilled, a sub-table mounted on the first one of said carriages, means for clamping said material to said sub-table which is made interchangeable, this means 20 comprising jaw members, a spindle and a crank-handle for operating said jaw members in either direction, said jaw members which have to serve as stops for the backs of the pieces of work, being capable of simultaneous adjustment in the longitudinal direction with respect to the axis of the drill spindle, an indicating scale for allowing said adjustment, the said means further comprising other jaw members, a spindle and a crank-handle for simultaneously 25 operating said last mentioned jaw members, said operation causing clamping of the pieces of work, guide means disposed in close proximity to the drill place and adapted for adjustment in transverse position to the tracks, this means being adapted for supporting a plurality of pieces of work, and means for supporting the free extremities of said pieces of work.
7. A device suitable for drilling section iron, comprising two stationary iron scaffolds of identical structure and disposed at both sides of the drilling device, tracks mounted upon both scaffolds, carriages adapted to travel on said tracks, the said carriages having the function to feed the material to the drill and to serve as a stop for the first perforation to be drilled, a sub-table interchangeably mounted on the first one of said carriages, means for clamping said material to said sub-table, this means comprising jaw members, a spindle and a crank-handle for operating said jaw members in either direction, said jaw members which have to serve as stops for the backs of the pieces of work, being capable of simultaneous 30 adjustment in the longitudinal direction with respect to the axis of the drill spindle, an indicating scale for controlling said adjustment, the said means further comprising other jaw members, a spindle and a crank-handle for operating said last mentioned jaw members, said operation causing clamping of the pieces of work, guide means disposed in close proximity to the drill place and adapted for adjustment in transverse position to the tracks, this means being adapted for supporting a plurality of pieces of work, and means for supporting the free extremities of said pieces of work.
8. A device suitable for drilling section iron, comprising two stationary iron scaffolds of identical structure and disposed at both sides of the drilling device, tracks mounted upon both scaffolds, carriages adapted to travel on said tracks, the said carriages having the function to feed the material to the drill and to serve as a stop for the first perforation to be drilled, a sub-table interchangeably mounted on the first one of said carriages, means for clamping said material to said sub-table, means for simultaneously adjusting said clamping means in the longitudinal direction with respect to the axis of the drill spindle, an indicating scale for controlling said adjustment, guide means disposed in close proximity to the drill place and adapted for adjustment in transverse position with relation to the tracks, means for operating said guide means which are adjustable with respect to the axis of the drill spindle, an indicating scale for controlling said adjustment, means for taking up the angle side pressure exerted on the pieces of work during the drill action, means for supporting the pieces of work and allowing same of being tipped into the reverse position for continuation of the drill action, an additional carriage mounted on said second carriage which is adapted for adjustment, a support carried by said additionally mounted carriage, jaw members disposed in said support, a common spindle for said jaw members, a crank-handle for operating said spindle and said jaws members simultaneously, square iron members in connection with said 40 jaw members, said square iron members, which are fastened to said support, serving as a stop for the material to be drilled, means for locking the additional carriage to the second carriage to prevent displacement thereof, a special support adapted for the reception of the material in clamped position thereby realizing a connection with the said second carriage, means movably disposed within guides and adapted to be raised and lowered, a rack-bar for operating said means so as to allow drilling of perforations in accordance with linear and root-scales, jaw members accommodated between said guides and adapted to be raised and lowered, a spindle and a crank-handle for operating said last mentioned 45 jaw members, said operation causing clamping of the pieces of work, guide means disposed in close proximity to the drill place, this means comprising a sub-table, still other jaw members, a spindle and a crank-handle for operation of said last mentioned jaws in either direction, identical spacings provided between the last mentioned and the first mentioned jaw members, the said last mentioned jaws being made adjustable with respect to the axis of the drill 50 spindle, an indicating scale for controlling said adjustment, rollers being provided for taking up the angle side pressure during the drill action, said rollers being of conical shape and disposed in oblique position, and having the function to maintain contact with the inner round corners of the pieces of work to prevent rough drill, rollers accommodated between the last mentioned jaw members and adapted for supporting the pieces of work, said rollers being mounted on a common flat iron bar and intended for tipping from one side to the other, thereby causing the pieces of work to occupy a reverse position and allowing of drilling perforations into the reversed angular 55 sides of the section iron pieces.
9. A device suitable for drilling section iron, comprising two stationary iron scaffolds of identical structure and disposed at both sides of the drilling device, tracks mounted upon both scaffolds, carriages adapted to travel on said tracks, the said carriages having the function to feed the material to the drill and to serve as a stop for the first perforation to be drilled, a sub-table interchangeably mounted on the first one of said carriages, means for clamping said material to said sub-table, means for simultaneously adjusting said clamping means in the longitudinal direction with respect to the axis of the drill spindle, an indicating scale for controlling said adjustment, guide means disposed in close proximity to the drill place and adapted for adjustment in transverse position with relation to the tracks, means for operating said guide means which are adjustable with respect to the axis of the drill spindle, an indicating scale for controlling said adjustment, means for taking up the angle side pressure exerted on the pieces of work during the drill action, means for supporting the pieces of work and allowing same of being tipped into the reverse position for continuation of the drill action, an additional carriage mounted on said second carriage which is adapted for adjustment, a support carried by said additionally mounted carriage, jaw members disposed in said support, a common spindle for said jaw members, a crank-handle for operating said spindle and said jaws members simultaneously, square iron members in connection with said 60 jaw members, said square iron members, which are fastened to said support, serving as a stop for the material to be drilled, means for locking the additional carriage to the second carriage to prevent displacement thereof, a special support adapted for the reception of the material in clamped position thereby realizing a connection with the said second carriage, means movably disposed within guides and adapted to be raised and lowered, a rack-bar for operating said means so as to allow drilling of perforations in accordance with linear and root-scales, jaw members accommodated between said guides and adapted to be raised and lowered, a spindle and a crank-handle for operating said last mentioned 65 jaw members, said operation causing clamping of the pieces of work, guide means disposed in close proximity to the drill place, this means comprising a sub-table, still other jaw members, a spindle and a crank-handle for operation of said last mentioned jaws in either direction, identical spacings provided between the last mentioned and the first mentioned jaw members, the said last mentioned jaws being made adjustable with respect to the axis of the drill 70 spindle, an indicating scale for controlling said adjustment, rollers being provided for taking up the angle side pressure during the drill action, said rollers being of conical shape and disposed in oblique position, and having the function to maintain contact with the inner round corners of the pieces of work to prevent rough drill, rollers accommodated between the last mentioned jaw members and adapted for supporting the pieces of work, said rollers being mounted on a common flat iron bar and intended for tipping from one side to the other, thereby causing the pieces of work to occupy a reverse position and allowing of drilling perforations into the reversed angular 75 sides of the section iron pieces.

- ing said jaw members which are connected by a bridge piece forming yoke over the object to be drilled, a die-rod laterally attached to said yoke which is adapted for horizontal movement in either direction and for raising and lowering holes provided in said die-rod and adapted for the removably made reception of drill-bushes corresponding in cross-section to various diameters of perforations to be drilled, 5 a steel tape-measure and rollers for supporting same, the said steel tape-measure which is of the endless type, being adapted to travel laterally of the framework and allowing of adjustment of the spacings, a protecting cover for 10 said steel tape-measure which is provided with 15

perforations, rollers made to engage with said perforations to prevent sliding of said steel tape-measure, means for tensioning said steel tape-measure, an illuminated hand at the reading-off place, means for causing said carriage to advance, this means comprising a single rope tackle block guided over pulleys provided with grooves disposed in helical line to allow operation of said rope in either direction, means for tensioning said rope drive, means for operating said rope drive and means for stopping the driving action, and a hand operated toothed wheel drive adapted for realizing accurate adjustment of the respective elements. 10

JOSEPH GORETH. 15
